United States Patent Office

Des. 219,466
Patented Dec. 15, 1970

219,466

TRAY FOR TOY TOPS OR THE LIKE

Anthony D. Miller, Torrance, Calif., assignor to Mattel,
Inc., Hawthorne, Calif., a corporation of Delaware

Filed Jan. 20, 1970, Ser. No. 20,996

Term of patent 14 years

Int. Cl. D21—02

U.S. Cl. D34—15

FIG. 3

FIG. 4

FIG. 1 is a rear perspective view of the upper portion of a tray for toy tops embodying my new design;

FIG. 2 is a front perspective view of the lower portion thereof;

FIG. 3 is a front perspective view of the upper portion thereof with the maze path removed; and

FIG. 4 is a rear perspective view of the lower portion thereof with the ramp attachment removed.

I claim:

The ornamental design for a tray for toy tops or the like, as shown and described.
